UNITED STATES PATENT OFFICE.

ALLAN C. RUSH, OF LOS ANGELES, CALIFORNIA.

BREAKWATER AND PIER AND METHOD OF MAKING THE SAME.

1,375,232.

Specification of Letters Patent. Patented Apr. 19, 1921.

Application filed June 26, 1916. Serial No. 106,075.

To all whom it may concern:

Be it known that I, ALLAN CYRUS RUSH, a citizen of the United States, residing at Los Angeles, in the county of Los Angeles and 5 State of California, have invented a new and useful Breakwater and Pier and Method of Making the Same, of which the following is a specification.

An object of this invention is to make provision whereby an ocean front in comparatively shallow waters may be converted into a harbor, and incidentally to this object the invention includes a pier base construction for loose formation such as sandy or mud 15 bottoms.

A principle of the invention in one of its applications is the construction of suitable pier bases spaced apart on a loose or sedimentary deposit and arranged to direct 20 wave, swell or current action into internal combat so as to neutralize the destructive force thereof and to protect the waters otherwise subject to such force, with a minimum expense of, and expense for, protective 25 structure.

It is well known that along many coasts there are shallow waters of sufficient depths for floating the largest vessels and yet unavailable for harbor purposes on account of 30 the danger from the high seas; and that it has heretofore been deemed impossible to build piers to protect such waters for the reason that the ocean bottom formation is loose for depths too great to allow the pier 35 substructure to reach a solid formation therebeneath without prohibitive expense or difficulty of construction.

An object of this invention is to provide a stable pier structure that will give a suitable foundation capable of resisting all the 40 forces and the stress and strain to which the same may be subjected.

The invention is not only capable of such use, but it is also adapted to afford a solid 45 and sufficient foundation for bridge piers on loose formation, thus allowing the erection of heavy bridge structures on ground heretofore regarded as impossible of use for such purposes.

50 The invention may be carried out in various ways and I do not limit the same to specific construction.

A principle of the invention resides in a determined construction of pier body where- 55 by the pier will cut in two the long waves

or swells and will break them up causing the water to lift itself and fall back to destroy its own momentum, with minimum destructive tendency toward breaking or undermining the pier. 60

An object is to stabilize a wave resisting pier or sea wall on a soft or loose bottom of sand, silt or sedimentary deposits.

I regard the invention as broadly new and pioneer in various features among which may be mentioned the formation of a sea-wall formed of individual piers spaced apart and arranged to direct the wave action to internal combat to neutralize the momentum of the waves and tide; the construction of a 70 pier with a forwardly projecting point with wave deflecting rear wings to break long swells and waves to destroy their force; the pier structure comprising a massive monolithic body adapted to have a superstructure 75 thereupon and resting on a sedimentitious bottom, and piles integral with such body and extending down from such body into such bottom; reinforcing means which interlock the piles and also serve as stabilizing 80 means for the pier; a bed of wood or other compressible material laid in the monolithic body on top of the piles for resiliently supporting the superstructure and the monolithic body above the wooden bed; a bed of 85 crossed iron rails on the wooden bed for reinforcing the monolithic body above the wooden bed and for distributing equally the weight of the superstructure and the monolithic body above the piles and the wooden 90 bed; and also the construction of the pier front receding rearwardly from an intermediate point and sloping rearwardly so as to break the waves and curl them over upon themselves so that each wave will tend 95 to destroy the force of a succeeding wave.

Other objects, advantages, and features of novelty may appear from the accompanying drawings, the subjoined specification and the appended claims. 100

The invention may be understood by reference to the accompanying drawings.

Figure 1 is a perspective view showing at low tide, bridge piers and breakwater piers constructed in accordance with this 105 invention.

Fig. 2 is a broken elevation partly in section of one of the units shown in Fig. 1. A portion of the temporary cofferdam made of joined piles is also shown. 110

Fig. 3 is an enlarged broken sectional detail elevation of the pier structure shown in Figs. 1 and 2, omitting the water.

Fig. 4 is a fragmental perspective partly 5 in section showing in completed construction, various details of the bridge pier shown in Fig. 1. The water is omitted.

Fig. 5 is a fragmental sectional elevation on a larger scale than the other figures, of 10 a pier in completed construction.

Fig. 6 is a plan of a pier base in completed construction before the cofferdam has been removed. Parts are broken away to show various features of construction.

15 Referring to Figs. 2, 5 and 6, the cofferdam *a* may be of any practical structure and is shown as constructed of tongue and groove piling of the character commonly in use for constructing cofferdams, said piling 20 being driven into the sand or mud bottom *b* to a depth sufficient to enable the operator to pump out the water, sand and other debris within said cofferdam *a*, to a suitable depth above the bottom of such cofferdam.

25 The piling 1 for the pier base structure may be of any appropriate length, say 150 feet more or less, and piling of this character may be 14 to 18 inches, more or less, in diameter at the upper end. These piles may 30 be of any suitable character and material, as wood, reinforced concrete or equivalents therefor, and are driven in any well known way as by hydraulic, electrical or drop weight means to a required depth in the sand 35 or mud bottom *b*. The work of driving said piles may be largely done before the cofferdam is built. After the cofferdam has been built and the piles 1 have been driven to such depth as may be convenient and appropriate, the water inside the cofferdam 40 will be pumped out, and thereupon the piles 1 may be cut off or driven to bring their tops to a depth or level below the level of the water surrounding the cofferdam. The piles 45 may be spaced apart a greater or less distance and are shown as being spaced about two feet apart. As the piles are driven down, they compress the soft bed between them and together with the compressed bed 50 form a strong and solid foundation.

When the cofferdam *a* has been constructed and the water inside the same has been pumped out, and the tops of the piles have been driven down or cut off to the required 55 depth, a mold *c* is placed upon the bottom and extends upward around the body or cluster of driven piles 1, and then a concrete filling of a more or less reinforced character is built within the mold *c* and directly 60 on the compressed and solidified bottom. The concrete filling 2 between the piles may be without reinforcement throughout its lower portion and the concrete collar 3 between the mold *c* and the body or cluster of 65 piles may be well supplied with reinforce-

ment 4 from the bottom to the top, so that the pile cluster is entirely surrounded by a reinforced concrete collar. The principal reinforcing elements 5 of the concrete between the piles may be located mainly near the level of the top of the piles as indicated by the railroad T irons 5, but ties 5' of iron, steel or other suitable material may be applied at appropriate points.

When the mold *c* has been filled with concrete with and without reinforcing as indicated in Fig. 5, to the tops of the piles, a cap 6 of wood or other suitable yielding material may be laid upon the concrete and the pile tops and projecting laterally beyond the pile tops, and upon the top of said wooden cap, two sets 7, 8 of reinforcing and structural irons, such as railroad T irons, are arranged in cross relation to each other, and the spaces between the reinforcing elements thus applied are filled in with concrete so that the cap 6 also is embedded therein, and finally the whole is entirely covered by a concrete layer 9, which may or may not be reinforced, according to the 70 judgment of the constructor. The work of construction is carried on in a well known manner so as to make a practically reinforced monolith of sufficient size, say, 400 feet in length by 300 feet in width. The 75 pier base is thus completed and preferably terminates below the level of the water outside of the cofferdam.

In this way the base structure, including the wooden piles, wooden cap, the reinforcing T rails, on top of said cap and the protecting cover 9 of concrete, are all below the level of the water at low tide, so that they are practically protected from atmospheric action. Upon the top of the covering a superstructure 10 of any suitable material may be built. Said superstructure is shown in the drawings as constructed of granite blocks.

In the course of construction, when the 110 mold *c* has been stationed on the bottom *b* a trench will be dug just inside the mold, so that as the concrete is poured, there will be formed a concrete lip or apron 11 which will extend down below the level of the bottom 12 of the main body of the concrete. This lip will be approximately two feet, more or less, in depth.

The purpose of this lip is to confine the upper portion of the soft formation on 120 which the pier base is formed.

It is understood that any depth of excavation may be made around the cluster of piles within the judgment and at the convenience of the constructor.

It may be found advisable to provide such a reinforcement for the structural piles 1 in addition to the ties 5, 5', 7 and 8, that the pier base is also stabilized thereby, and for this purpose the piles are preferably con- 130

nected by means of bands, links or rings 13 of galvanized iron, steel or other suitable material applied at intervals from the level of the soft bottom b to the top of said piles.

5 The pile connecting means 13 may be put in place by the workmen above the concrete from time to time as the level thereof rises during construction; and then the concrete is filled in to surround and cover the same 10 so that in the completed structure the piles are tied together throughout the whole cluster and become integral parts of a reinforced concrete structure and extend to a great depth below the concrete body thereof.

15 Said piles may or may not extend to bed rock indicated at d in Fig. 3.

In the process of driving the piles it is deemed desirable to begin centrally of the space to be covered and to drive piles there- 20 around until the requisite number of piles are driven. By this method, the consolidation of the mud, silt or sand caused by driving the piles, need not be such as to prevent driving the piles by an ordinary pile-driver 25 but a great consolidation of the bottom b is thus effected.

The overhanging or projecting collar 3 is symmetrically arranged relative to the cluster of piles and said cluster as a whole has 30 a coefficient of strength and stability far in excess of that to which the structure may be subjected.

The downwardly extending lip 11 incloses an upper stratum of the soft bottom b , and 35 the hydrostatic pressure tends to force the soft bottom up into the space between the lip 11 and the cluster of piles 1 and the interstitial filling formed between the piles by the soft bottom b ; thus adding greatly to 40 the ultimate strength of the structure.

It is understood that where deposits of silt, sand, or the like occur, there may in course of time occur changes of current tending to wash away the bottom b and this 45 is guarded against by the depth of piles below the surface. If the bottom is cut away on one side, the piles thus exposed become resisting elements held in place by the interlocked mass of piles, reinforcing, ties 50 and concrete.

In some instances heavy masses and blocks of stone e may be filled into the space around the lip thus giving additional protection.

The piers constructed as set forth may be 55 located to face the open sea as indicated at 14 in Fig. 1 and may be used as bridge piers as indicated at 14' in said Fig. 1, it being understood that the pier construction in each instance is practically the same.

60 Each pier is provided with one or more prow like projections 15, and their front surfaces are somewhat conformed to the shape of a double mold board plow and serve as deflectors, being curved in horizon- 65 tal traces as at 16 and receding rearwardly

on each side of the central projection or nose 15, and the faces 17 slant upward and backward and are curved both in vertical and horizontal directions and are provided along the bottom with a riser 18, its top 70 sloping upward from the central point or nose 15 so that waves impinging against said pier will be deflected laterally and up, and so that the force of the waves is exerted measurably downward to hold the structure 75 in place and the energy is expended largely in lifting the water by its own action.

The piers are arranged adjacent to each other close enough together to cause the deflected waters from two adjoining piers to 80 combat each other thus neutralizing their forces.

Front faces 17, 18 may be provided on two sides of the same pier as shown so as to take care of wave action from different directions at different times. This may sometime prove of great service, as at the mouths of rivers or estuaries where destructive forces, floods and tides may occur.

It is understood that the dimensions and 90 relative proportions may vary greatly to accommodate different conditions. In some instances the breakwater or sea wall protector for a harbor f may be formed of a series of piers 14 of 400 feet length and 300 95 feet width and 50 feet depth, the piles 1 being formed as integral downward extensions thereof seated in the sedimentary bed b upon which the bottom 12 of the monolithic body rests. The surrounding reinforced 100 concrete collar 3 may extend 30 feet, more or less, beyond the pile cluster and may be 50 feet, more or less, in depth, and may be more or less submerged.

On an open coast an incoming wave may 105 be many hundred feet long and may come landward with tremendous power. In practical operation such wave meets the sharp point of the pier and is cut in two. This lessens its power, and the momentum of the 110 upper portion of the wave being greater than that of the lower portion, the upper portion rises as it advances, and pushes on and part of it drops back and part is too strong and deflects to each side of the pier. 115

The deflected water from adjacent piers 120 coacts and the line of piers is thus made effective as a breakwater. The deflected portions of the wave come together between the two breakwater sections 14, strike upon each other and destroy their own power with the result that this form of breakwater will take the place of a solid wall that under the practice of the prior art could only be effective if constructed the full length of sea front to 125 be protected, at a very much greater expense, which in many instances would be prohibitive where this feature of this invention would make the project perfectly feasible.

The crossed railway iron with the interstitial concrete forms a heavy, rigid and solid bed on top of the piles so that the pressure above the piles to support the superstructure will be equally distributed over the cluster of piles. It should in this connection be noted that the cap is of a compressible material and therefore resiliently supports the superstructure and the monolithic base above the piles and the cap, thereby allowing the center of the superstructure to settle somewhat and thus to compensate the external settling of the piling and to compact the sand or silt within the compass of the piling.

The heavy weight of the T-rail bed or its equivalent also serves to give great resisting power to the pier.

The pier construction is especially adapted for supporting heavy bridge superstructures as the piers of suspension bridges on the opposite sides of rivers or other wide spaces to be bridged.

The yielding character of the central cap formed of wooden timbers and T rails over the piles which are more positively founded than the soft bottom between the cofferdam and the piles adds to the strength of the pier and tends to compensate for inequalities of subsidence relative to the pile supported center and the soft bed supported rim of concrete outside the piles.

It is understood that the dimensions mentioned herein are not arbitrary and that they and other features of construction may be changed within the judgment of the constructor without departing from the spirit of the invention.

I claim:

1. A pier having a forward projection 40 and rearwardly extending curved faces sloping upwardly from the front toward the rear, the lower edge of said upward slope being higher at the ends of said curved faces than at said projection so that the 45 water impelled by wave action will be lifted and at the same time deflected laterally to neutralize its own momentum.

2. A series of piers forming a breakwater outside of a shore, each pier having a forward projection and rearwardly extending curved faces sloping upwardly from the front toward the rear, and the lower edge of the upward slope being higher at the ends of the curved faces 50 than at the projection so that the water impelled by the action of the waves will be lifted and deflected for the purpose of neutralizing its own momentum.

3. A series of piers spaced apart and forming a breakwater outside of a shore, 60 each pier having a forward projection and rearwardly extending curved faces sloping upwardly from the front toward the rear, and the lower edge of the upward slope being higher at the ends of the curved faces 65 than at the projection so that the water impelled by the action of the waves will be lifted and deflected for the purpose of neutralizing its own momentum.

In testimony whereof, I have hereunto set 70 my hand at Los Angeles, California, this 21st day of June, 1916.

ALLAN C. RUSH.

Witness:

JAMES R. TOWNSEND.
